G. Pack,
Making Staves.
Patented Oct. 10, 1835.

George Pack's
Letter Patent

The Schedule referred to in these Letters Patent and making part of the same containing a description in the words of the said George Pack himself, of his improvement in the machine for cutting staves from steamed timber.

Be it known that George Pack of Sullivan in the County of Madison and State of New York have invented a new and useful improvement in the manner of making staves and that the following is a full and exact description of the construction and operation of the machine used for that purpose.

Though it is necessary to premise that the timber either in the shape of bolt, plank, round block or sawed stuff, is to be steamed first previous to presenting it to the action of the machine. And this is best done after it is cut off to the required length. Boiling may be employed at the option of the operator, the intention being to render the wood so yielding and tough or elastic as not to split as the knife goes through. In the construction of the machine I first make a long frame consisting of two pieces of timber forming the sides to be fixed upon cross sills at each end. At one end of this frame is secured a revolving shaft properly secured in boxes; one placed on a side piece and the other on an additional one attached to the opposite end of the cross sills which a cog wheel is here added to the end of the shaft for the purpose then project beyond the side piece for that purpose of gearing on to the propelling power (which may be discretionary). The shaft is to be furnished with rows of arms or rays for the purpose hereafter described. At a little distance beyond this shaft is to be placed an upright on each side piece & through the tops of these another small shaft is to pass from one to the other & projecting a short distance beyond each, these projections

four pivots on which is to swing the knife frame consisting of two sides connected by cross pieces leaving the pivots playing a little in advance of the centre of the sides. On the top of the cross pieces & parallel with the sides are placed one or more levers sufficiently long to reach from one or more rows of eggs on the main revolving shaft (and on which the ends of said lever rest) to the other ends of the knife frame where they press upon the back of the knife placed below them & extending from one end of the side piece to the other opposite one. This knife or consists of a broad flat, blade as long as the staves and having the lower edge sharp and extended edgewise across the frame. A little beyond this balancing knife (which has also a broad block extended from one side piece of the main frame to the other directly under it) is placed a feeding carriage some what after the fashion of a saw mill consisting of two sides & a middle piece (something shorter) connected together horizontally by cross pieces so as to form another frame narrower and longer than the knife one. At the ends of these sides next the knife are placed iron plates on the inside which are roughened the better to answer their purpose of holding the bolt or piece of stuff to be cut up. Between them and that end they form jaws, one being a movable one, by placing it outside of the side piece & to play as a joint on the end of the cross piece situated at that end. At long spaces and so as to pass through them by turning which they may be tightly joined together or released at pleasure. On the centre shaft middle piece is placed a rack and over it a hand wheel by being thrust forward advances the carriage on the side & groove beneath it & this hand joint loosely on to an upright rising from an horizontal axle playing up above the feeding carriage and between two uprights secured into the side pieces of the main frame. At the end of this axle is secured permanently a long lever which

which reaches to the row of eggs on the end of the main shaft, & extends beyond the sides of the main frame for that purpose. Operation. The steamed timber being placed between the jaws of the feeding frame the main axle is set in motion and the rows of eggs & the wheel raise the long lever resting thereon which by its connection & with the hand moves it back and then by the weight of the lever on falling beyond the egg on the axle advances the said hand and consequently with it the piece of steamed or boiled timber contained between the jaws. The pressure of the eggs upon the axle also raises up the ends of the lever laid on top of the knife frame. This balances on its pivot and consequently forces down the knife at the opposite end through the piece of timber, the front side of the knife having that part rounded so as to allow it to advance freely through the wood, & the knife edge planed on the whole length of the blade (which cuts across the frame) so as to divide the whole length with the grain at once. The rapidity of motion of the knife frame will depend on the number of eggs. (What I claim as my invention in the above described operation is - The formation of staves from steamed or boiled wood, cut with an edge tool or knife after the manner and according to the combination above set forth in my machine, consists of the main axle and the feeding frame to operate with the knife frame of which I claim the construction and use as adopted to the purpose above mentioned. In testimony that the above is a full and exact description of the construction and operation of my machine as invented or improved by me. I have hereunto set my hand this eight day of September eighteen hundred and thirty five
